Primary Examiner—Jennifer Rivard*Assistant Examiner*—Rosemary K Tarcza(74) *Attorney, Agent, or Firm*—Brinks Hofer Gilson & Lione(57) **CLAIM**

We claim the ornamental design for a battery for personal computer, as shown and described.

DESCRIPTION

FIG. 1 is a front perspective view of a battery for personal computer of the present invention;

FIG. 2 is a rear perspective view thereof;

FIG. 3 is a front view thereof;

FIG. 4 is a rear view thereof;

FIG. 5 is a first side view thereof;

FIG. 6 is a second side view thereof;

FIG. 7 is a top view thereof; and,

FIG. 8 is a bottom view thereof.

The broken line showing of battery for personal computer is included for the purpose of illustrating environment and forms no part of the claimed design.
